**LEVEL INDICATOR FOR FORK TYPE
LIFT TRUCKS**

Allen E. Bertenshaw, Markham, and Francis J. Bazata,

pany, Chicago, Ill., a corporation of New Jersey
Filed Nov. 23, 1959, Ser. No. 854,689
1 Claim. (Cl. 214—674)

This invention relates to an indicating device. More specifically the invention relates to a device used on a fork type lift truck which is adapted to indicate the position of the horizontal forks to an operator.

The present invention has to do with a lift truck generally utilized in material handling and particularly adapted for moving articles. Such a truck is shown in the Repke Patent 2,456,320, patented December 14, 1948. In a lift truck of this type a vertical lifting frame is pivotally mounted on the forward end of a wheeled tractor or truck. The lifting frame supports a fork type lifting platform which is vertically movable on the vertical frame for raising and lowering pallets and the like. Generally the lifting platform is raised by means of hydraulic rams and the vertical frame may be tilted from the vertical slightly forwardly or rearwardly by means of another suitable hydraulic ram. The tilting movement of the vertical frame results in the tilting of the horizontal platform from the horizontal to a downwardly or upwardly inclined position. The tilting arrangement is desirable to facilitate the entry of the fork platform underneath objects to be lifted or into the recesses of suitable pallets. For instance the lifting platform may be inclined downwardly while the truck is moving in a forward direction and thus an object seated upon floor may be engaged whereupon the fork may then be tilted upwardly to retain the object on the fork while it is raised to the desired position. In order to expedite material handling with this type of truck it is extremely desirable that the operator, at any given time, knows the position of the platform with regard to the horizontal or an inclined position. Also the degrees of inclination are extremely important. Thus it is a prime object of the invention to provide an improved indicating device which is readily visible from the operator's station and which will promptly indicate the position of a lifting type platform.

Another object is the provision of a simplified indicator particularly adapted for lift type trucks, the said indicator including a minimum of parts and being adapted to provide visual indicating means to an operator to indicate the tilted position of a lifting platform.

A still further object is to provide an indicator for lift type trucks, the said indicator including a pair of relatively movable indicating elements hingedly connected to a vertical frame of the lifting platform and to the body of the truck, the said elements being movable simultaneously with the vertical lifting frame to indicate the position of a lifting platform.

These and other objects will become more readily apparent from a reading of the specification when examined in connection with the accompanying sheet of drawing.

In the drawing:

FIGURE 1 is a side elevational view of the forward portion of a fork type lift truck having an improved indicating means positioned thereon and showing a lifting platform in position adjacent a palletized object;

FIGURE 2 is an enlarged side elevational view, partially in section, showing an indicating device for lift trucks; and

FIGURE 3 is a plan view, of reduced scale of the indicating device shown in FIGURE 2.

2

Referring now particularly to FIGURE 1, a fork type lift truck is generally designated by the reference character 10. The truck 10 comprises a body 11 suitably supported on ground wheels 12. Only the forward portion of the truck is shown and it is generally conventional in detail, as shown for instance in the aforementioned patent. The body 11 is provided with an operator's station 13 and the wheels 12 are steered by a suitable steering wheel 14. A supporting platform 15 is mounted on the forward end of the body 11. The supporting platform 15 supports a vertical lifting frame 16 by means of a suitable hinge 17.

A lifting platform is generally designated at 18, the said platform 18 comprising a pair of horizontally extending laterally spaced forks 19 suitably connected to vertical supports 30 which in turn are connected to a raising and lowering means (not shown) positioned within the lifting frame 16. A fluid cylinder is indicated at 21. The fluid cylinder 21 is pivotally supported on the body 15 by means of a pivot 22 and includes suitable fluid conduits 23 which alternately supply fluid under pressure to opposite ends of the cylinder 21 for reciprocating a ram or piston rod 24 which is pivotally connected to the lifting frame 16 as indicated at 25.

An indicating device, best shown in FIGURES 2 and 3, is designated by the reference character 26. The indicating device 26 comprises a pair of spaced brackets 27 suitably connected to the body of the vehicle 11 as shown in FIGURE 1. A first indicating member 28, in the form of a round or rectangular tube, is hingedly connected to the bracket 27 by means of a transversely extending hinge pin 29 as shown in FIGURE 3. The indicating member 28 is provided with inner walls 30, the top inner wall 30 being suitably cut out to provide a slot 31 as best shown in FIGURE 3. The slot 31, by virtue of the position of the indicating device 26, as shown in FIGURE 1, is readily within sight or view of the operator on the operator's station 13. A pair of indicating means or blocks 32 are suitably connected to the member 28 in transversely aligned relation as shown in FIGURE 3. A second indicating member is designated at 33, the said member 33 being slidably or telescopingly positioned within the first indicating member 28. The second indicating member 33 is provided at one end with an opening 34 through which a hinge pin 35 is placed, the said hinge pin 35 being suitably secured to the vertical frame 16 so that the second indicating member 33 is hingedly connected thereto. The indicating member 33 also includes a transversely extending bar or suitable indicia marking 36 which is adapted to be transversely aligned with the blocks 32 in a certain position of the member 33 relative to the member 28.

In FIGURE 1 the truck 10 is shown in position relative to a pallet 37 of conventional construction. In operation the forks 19 of the lifting platform 18 may be moved into engagement with the pallet 37, which is provided with the usual recess (not shown) within which the forks 19 may be placed. In the entry into the pallet 37 the forks 19 are positioned in a horizontal position and upon engagement it may be desirable to incline the lifting frame 16 rearwardly to the broken line position shown in FIGURE 1 to assure that the pallet 37 is positively placed on the lifting platform 18. To achieve this inclination rearwardly the fluid device 21 is actuated so that the ram 24 moves rearwardly. Conversely, if it is desired to incline the forks from the horizontal downwardly the frame 16 is moved to a forward position as shown in the broken line arrangement of FIGURE 1. Besides lifting of palletized objects there are many instances where inclination of the forks is desired depending upon the material handling operation to be performed. Thus it is highly desirable that the operator very quickly

and positively knows the exact position of the fork. Thus the indicating device 26 effectively discloses the position of the forks 19. For instance if the lifting platform 16 is moved forwardly the indicator 36 is moved to the position shown in FIGURE 3 at A. If the lifting frame 16 is moved rearwardly, the indicator may be moved to the position shown in FIGURE 3 at B. In the level position the indicator 36 is in transverse alignment with the blocks 32. Thus the operator knows the exact position of the forks with respect to the horizontal or upwardly or downwardly inclined positions. It is, of course, readily apparent that additional indicating means similar to 32 may be employed on the member 28 to indicate the inches or degrees of tilting as desired. Thus by simply glancing at the indicator the operator at all times known the position of the forks 19. This greatly facilitates the material handling operations since it is often difficult to know exactly the position of the forks 19.

Thus it is believed that the objects of the invention have been clearly achieved and it must be understood that changes and modifications may be made without departing from the spirit of the invention as disclosed or from the scope thereof as defined in the appended claim.

What is claimed is:

A position indicating device for a lift truck having a body, a vertical lifting frame connected to said body, a vertically movable normally horizontal lifting platform connected to said lifting frame, and fluid extensible means connected to said body and said vertical frame for tilting said frame forwardly and rearwardly of said body

20 25 30

whereby said platform is tilted from a horizontal position to an upwardly inclined or downwardly inclined position; comprising a bracket connected to said body, a tubular member hingedly connected to said bracket, said tubular member having an elongated slot disposed in a position within sight of an operator on said truck, an indicating member disposed within said tubular member in relative sliding relation, said indicating member having a first indicating means thereon visible through 5 10 15 said slot, a second indicating means on said tubular member disposed adjacent said slot, and means hingedly connecting said indicating member to said vertical frame whereby on tilting of said frame said first indicating means is moved relative to said second indicating means to a position denoting a horizontal or tilted position of said platform.
